US0D1100101S

(12) **United States Design Patent** (10) **Patent No.:** **US D1,100,101 S**
(45) **Date of Patent:** **** Oct. 28, 2025**

(54) **ASSEMBLED SLIDE**

(71) Applicant: **Crowntec (Jiang Xi) Sports Technology Co. Ltd.**, Jiujiang (CN)

(72) Inventor: **Soebagijo Nirwan**, Jiujiang (CN)

(73) Assignee: **Crowntec (Jiang Xi) Sports Technology Co. Ltd.**, Jiujiang (CN)

(**) Term: **15 Years**

(21) Appl. No.: **29/942,379**

(22) Filed: **May 15, 2024**

(51) LOC (15) Cl. **21-03**

(52) U.S. Cl.

USPC **D21/818**

(58) **Field of Classification Search**

USPC D21/811, 814, 818, 819, 828
